UNITED STATES PATENT OFFICE.

JAMES L. VAUCLAIN, OF LAFAYETTE, INDIANA.

IMPROVEMENT IN LOCOMOTIVE FIRE-BOXES.

Specification forming part of Letters Patent No. **33,057**, dated August 13, 1861.

To all whom it may concern:

Be it known that I, JAMES L. VAUCLAIN, of Lafayette, Tippecanoe county, State of Indiana, have invented new and useful Improvements in the Fire-Boxes of Locomotives, &c.; and I do hereby declare the following to be a full, clear, and exact description thereof, reference being had to the accompanying drawings, making part of this specification.

My invention relates to a form of bottom for a locomotive fire-box which, while preserved from burning and increasing the effective heating-surface, is so arranged as to be capable of an instantaneous increase or diminution of its draft-passages at will of the engineer.

The accompanying drawing is a longitudinal section through a fire-box with my improved bottom.

A is the inner shell inclosing the fire-chamber B.

C C' is the outer shell of the boiler, between which and the shell A intervenes a "water-jacket," D. This jacket is, in the present arrangement, continued entirely under the floor E of the fire-chamber B, draft-passage being afforded, and the inner and outer plates of the bottom being effectually stayed to each other by a series of equidistant hollow stay-bolts, F.

G is a stout plate having apertures g, which correspond to those of the hollow stay-bolts F in the bottom of the fire-box. The thus-perforated plate G is secured snugly beneath the said bottom in such a manner as to permit of a sliding movement by the engineer, by which the plate (register) G g may be shifted so as to bring its apertures immediately under the blank spaces of the fire-box bottom, or partially so, according to the amount of draft and activity of combustion that may be required. A lever, H, connected with the register G g, is placed so as to have its handle conveniently located for use.

I claim as new and of my invention—

The combination of the double fire-bottom C' E, hollow stay-bolts F, water-jacket D, and register G g, perforated to correspond with the fire-bottom and sliding beneath the same, the whole being constructed and arranged and operating in the manner and for the purposes explained.

In testimony of which invention I hereunto set my hand.

JAMES L. VAUCLAIN.
